DOOR KNOB ESCUTCHEON PLATE

Richard J. Ohno, Branford, Conn., assignor to Sargent & Company, New Haven, Conn., a corporation of Connecticut

Application April 8, 1954, Serial No. 29,919

Term of patent 7 years

(Cl. D50—6)

Fig. 1.

Fig. 2.

Fig. 3.

Fig. 1 is a front elevational view of a door knob escutcheon plate embodying my new design;

Fig. 2 is a side elevational view of the plate; and

Fig. 3 is a top plan view.

I claim:

The ornamental design for a door knob escutcheon plate, substantially as shown.
